SISSY BAR FOR MOTORCYCLES

Harold L. Hartlaub, Hanover, Pa., assignor to A & H
Cycle Accessory Company, McSherrystown, Pa.

Filed Oct. 16, 1975, Ser. No. 622,941

Term of patent 14 years

Int. Cl. D12—11

U.S. Cl. D12—119

Fig. 1

Fig. 3

Fig. 2

FIG. 1 is a front elevation view of a sissy bar for motorcycles showing my design.

FIG. 2 is a side elevation view thereof.

FIG. 3 is a top plan view thereof.

The rear of the sissy bar is substantially the same as the front shown in FIG. 1. The broken lines in the drawing are for illustrative purposes only.

I claim:

The ornamental design for a sissy bar for motorcycles, substantially as shown and described.
